TOY FIGURE

Joseph L. Kallus, Brooklyn, N. Y.

Application June 12, 1941, Serial No. 397,664

1 Claim. (Cl. 46—173)

My invention relates to toy figures such as dolls, toy animals and the like, and more particularly to jointed toy figures having bodies and other members made of highly flexible material such as soft rubber, fabric and the like. Because of the inherent yielding or non-rigid characteristics of the soft rubber, fabric or equivalent material, considerable difficulty has heretofore been experienced in combining the parts of the figures in a manner to provide efficient arrangements of joints which will withstand use and permit adjustment of the various parts of the figures in a natural and life-like manner.

The invention has for its object to provide novel constructions in which these difficulties are overcome and in which the body of each toy figure and associated members are connected in jointed relation in a simple and efficient manner.

Other objects will appear from the description hereinafter, and the features of novelty will be pointed out in the claim.

In the accompanying drawing, which illustrates examples of the invention without defining its limits,

Fig. 1 is a fragmentary sectional view of a doll embodying the novel features;

Fig. 2 is a detail sectional view illustrating the neck portion of the doll at one stage of construction;

Fig. 3 is a similar view of the leg and arm socket arrangement;

Fig. 4 is a fragmentary section showing a portion of the body at the arm and leg sockets;

Fig. 5 is a detail sectional view of another form of the novel limb construction, and

Fig. 6 is a similar view of another form of the novel neck arrangement.

In the illustrated examples of the invention, the novel features are shown as embodied in dolls having jointed or relatively movable heads, legs and arms, for which they are particularly adapted. It is to be understood, however, that the examples shown in the drawing have been selected for illustrative and descriptive purposes only and that the novel features may be utilized with equal efficiency in connection with other types of jointed toy figures such as toy animals, etc., and the description and claim are to be construed accordingly.

As shown in the drawing, the doll comprises a hollow body 10 which is constructed of soft sheet rubber or other equivalent highly flexible material, such as a suitable fabric, or the like. In the finished condition the body 10 is filled in the conventional manner with any suitable filling mate-

rial 11 customarily used for this purpose to give the desired form and effect to said body 10. At its upper end the body 10 is formed with a continuing neck section 12 which in its initial condition includes an integral tubular sleeve section 13 as shown in Fig. 2.

The doll further includes a neck member 14 of wood or other suitable rigid material and predetermined shape; for instance, as shown, the outer 10 surface of said member 14 may converge upwardly from a sloping annular flange 15 to a rounded upper end 16 as illustrated in Figs. 1 and 2. The neck member 14 is provided with an upwardly open axial recess 17 and a continuing axial opening 18 which terminates at a recess 19 preferably formed in the bottom or inner end surface of said neck member 14 as shown in Figs. 1 and 2. In the finished condition of the doll, the neck member 14 is located within the neck section 12 of the body with the tubular sleeve section 13 turned inwardly into the axial recess 17 in surface engagement with the surface thereof as shown in Fig. 1. Prior to its insertion into the recess 17 the tubular section 13 may be cut to the proper length, if necessary, to properly fit into said recess 17. The section 13 may be secured in the recess 17 in any convenient manner as by means of a plug 20 dimensioned to fit into the recess 17 in a manner to clamp the sleeve section 13 in 25 said recess 17, and provided with an axial bore 21 as illustrated in Fig. 1. The plug 20 may be made of wood or other suitable material, and in its operative position preferably rests upon the bottom of the recess 17 with its axial bore 21 in registry with the opening 18. Friction alone may be relied upon to fix the plug 20 in place in the recess 17 to properly clamp the section 13 therein, or if desired said plug 20 may be cemented or otherwise secured in its operative position. The

40 doll's head 22 which may be of any conventional type and material, is provided with an opening 23 whereby said head 22 is movably mounted on the neck section 12 of the body as shown in Fig. 1. The head 22 may be movably combined with the 45 body 10 or specifically the neck section 12 thereof in any well-known way as by means of an elastic band 24. In such arrangement the band 24 may have its one end connected with a cross-pin 25 located in the recess 19 of the neck member 14 and 50 spanning the opening 18 thereof, and its other end suitably secured in the interior of the head 22 in any customary manner. As illustrated in Fig. 1, the elastic band 24 passes through the opening 18 and bore 21 of the plug or sleeve 20 to the interior of the head 22 to enable the latter to be relatively

shifted in simulation of the natural movements of the human head.

In addition to the parts so far described, the body 10 is provided with arm sockets 26 of circular concave form and continued in the form of preferably cylindrical sleeve sections 27 provided at their inner ends with inwardly directed annular flanges 28. Because of the inherent flexibility of the material of which the body 10 and the integral sockets 26 are constructed, the latter are supported by interior supporting devices or reinforcing members 29 made of wood or other suitable rigid material. The supporting devices or reinforcing members 29 may be of any convenient external form and include end faces 30 of circular concave form corresponding to the circular concave form of the sockets 26. The supporting devices or reinforcing members 29 are further provided with preferably circular recesses 31 open at the end faces 30 and communicating with axial openings 32 of relatively reduced diameters and open at the inner ends of the supporting devices or members 29 as illustrated in Figs. 1 and 3.

In the assembled condition of the parts the material of the body 10 which forms the arm sockets 26 is located in surface engagement with the circular concave end faces 30 of the supporting devices or reinforcing members 29 with the cylindrical sleeve sections 27 of said arm sockets 26 extending into the circular recesses 31 of said devices or members 29 in surface engagement with the walls thereof and the inwardly extending flanges 28 resting in engagement with the bottoms of said recesses 31 as shown in Fig. 1. The body material comprising the arm sockets 26, sleeves 27 and flanges 28 is combined with the supporting devices or reinforcing members 29 by means of plugs 33 dimensioned to snugly fit into the recesses 31 in a manner to clamp the sleeve sections 27 therein and to clamp the flanges 28 against the bottoms of said recesses 31. The plugs 33 are formed with cylindrical extensions 34 dimensioned to snugly fit into the axial openings 32 of the devices or members 29 so as to be rigidly fixed in place by frictional engagement with the surfaces of said openings 32 or by being cemented or otherwise secured therein; preferably the extensions 34 are of less axial length than the axial length of the openings 32 as shown in Fig. 1. The plugs 33 in addition are formed with circular concave faces 35 corresponding to the circular concave form of the arm sockets 26 and forming therewith a continuous socket of circular concave form as illustrated in Fig. 1. In addition the sleeves 33 and extensions 34 are provided with axial bores 36 opening at the concave surfaces 35 and the inner ends of said extensions 34 respectively, as shown in Figs. 1 and 3.

The arm members 37 of the doll are constructed of soft sheet rubber or other equivalent highly flexible material such as a suitable fabric or the like, and are hollow, said arm members in the finished condition being filled in the conventional manner with any suitable filling material 38 customarily used for this purpose to give the desired form and effect to said arm members 37. At their upper ends the arm members 37 are formed with spherical sections 39 adapted to fit the arm sockets 26 in the assembled condition of the doll to provide shoulder joints on which said arm members may be adjusted relatively to the body. To provide the necessary rigidity to the flexible material of which

the arm members 37 are constructed, the spherical end sections 39 are internally reinforced by means of reinforcing members or supporting devices 40 illustrated in the form of spheres of wood or other suitable rigid material. The reinforcing members or supporting devices 40 are provided with inwardly directed recesses 41 open at the outer surfaces of said devices or members 40 and adapted to receive tubular or sleeve sections 42 comprising integral parts of the spherical end sections 39 of the arm members 37 and extending into the recesses 41 of the reinforcing members or supporting devices 40 in surface engagement with the walls thereof. The sleeve sections 42 are fastened in the recesses 41 by means of plugs 43 of wood or other suitable material and dimensioned to snugly fit into place in a manner to securely clamp said sleeve sections 42 in place in said recesses 41. Friction alone may be relied upon to maintain the plugs 43 in their operative positions or said plugs 43 may be cemented or otherwise secured in place if this should be deemed necessary or desirable. The plugs 43 are provided with axial bores 44 extending through said plugs 43 and registering with axial openings 45 provided in the spherical reinforcing members or supporting devices 40, it being understood that in the assembled condition of the parts the plugs 43 preferably rest against the bottoms of the recesses 41 as shown in Fig. 1.

When combined with the body 10 the spherical end sections 39 of the arm members 37 are located in the arm sockets 26 in surface engagement therewith as illustrated in Fig. 1. Any suitable means may be provided for movably combining the arm members 37 with the body 10 or in other words, to movably fix the spherical end sections 39 in the arm sockets 26. As shown in Fig. 1 this means may comprise elastic bands 46 extending through the axial bores 36 of the plugs 33 and extensions 34 and into the axial bores 44 of the sleeves 43 and having their one ends connected to pins 47 lying in engagement with the end faces of the extensions 34. The other ends of said elastic bands 46 as shown may be connected with the hooked ends of fastening pins 48 extending through the axial openings 45 of the reinforcing members or supporting devices 40 and having heads 49 preferably located in recesses 50 formed therein as illustrated in Fig. 1.

At the proper points the body 10 may further be provided with leg sockets 51 of circular concave form and continued in the form of preferably cylindrical sleeve sections 52 provided at their inner ends with inwardly directed annular flanges 53. Reinforcing members or supporting devices 54 corresponding to the members or devices 29 and likewise made of wood or other suitable rigid material serve to rigidly support the leg sockets 51 in a manner similar to that previously described with respect to the arm sockets 26. The supporting devices or reinforcing members 54 may be of any convenient external form and include end surfaces 55 of circular concave form corresponding to the circular concave form of the leg sockets 51. The supporting devices or reinforcing members 54 are further provided with preferably circular recesses 56 for the accommodation of the sleeve sections 52 and flanges 53, it being understood that the sleeve sections 52 are located in surface engagement with the walls of the recesses 56 while the flanges 53 are in engagement with the bottoms thereof as illustrated in Fig. 1.

The body material comprising the leg sockets

51, sleeves 52, and flanges 53 is combined with the supporting devices or reinforcing members 54 by means of a plug 57 dimensioned to snugly fit into the recesses 56 in a manner to clamp the sleeve sections 52 therein and to clamp the flanges 53 against the bottoms of said recesses 56. The plugs 57 are formed with cylindrical extensions 58 dimensioned to snugly fit into the axial openings 59 with which the reinforcing members 54 are provided as shown in Fig. 1 so as to be rigidly fixed in place by frictional engagement with the surfaces of the openings 59 or by being cemented or otherwise secured therein; the extensions 58 are preferably also of less axial length than the axial length of the openings 59 as illustrated in Fig. 1. The plugs 57 in addition are formed with circular concave faces 60 corresponding to the circular concave form of the leg sockets 51 and forming therewith a continuous socket of circular concave form as shown in Fig. 1. The plugs 57 and extensions 58 in addition include axial bores 61 opening at the concave surfaces 60 and the inner ends of said extensions 58 in a manner similar to that previously described with respect to the arm sockets.

The leg members 62 are constructed of soft sheet rubber or other equivalent highly flexible material such as a suitable fabric or the like, and are hollow and filled in the conventional manner with any suitable filling material 63 customarily used for this purpose, to give the desired form and effect to said leg members 62. At their upper ends the leg members 62 are formed with spherical sections 64 adapted to fit the leg sockets 51 in the assembled condition of the doll to provide joints on which said leg members may be adjusted relatively to the body. As in the arm members 37 the necessary rigidity is provided for the spherical end sections 64 by means of reinforcing members or supporting devices 65 illustrated in the form of spheres of wood or other suitable rigid material. The members 65 are provided with inwardly directed open ended recesses 66 adapted to receive tubular or sleeve sections 67 comprising integral parts of the spherical end sections 64 of the leg members 62 and extending into the recesses 66 in surface engagement with the walls thereof. The sleeve sections 67 are fastened in the recesses 66 by means of plugs 68 of wood or other suitable material dimensioned to snugly fit into place in a manner to securely clamp said sleeve sections 67 in place in the recesses 66. Friction alone may be relied upon to maintain the plugs 68 in their operative positions, or said plugs 68 may be cemented or otherwise secured in place if this should be deemed necessary or desirable. The plugs 68 are provided with axial bores 69 extending through said plugs 68 and registering with axial openings 70 provided in the spherical reinforcing members 65, it being understood that in the assembled condition of the parts the plugs 68 preferably rest against the bottoms of the recesses 66 as illustrated in Fig. 1.

In the assembled condition of the parts, the spherical end sections 64 of the leg members 62 are located in the leg sockets 51 in surface engagement therewith so as to be capable of more or less universal movements relatively to the body 10. Any suitable means may be provided for maintaining the leg members 62 in movable connection with the body 10, or, in other words, to movably fix the spherical end sections 64 in the leg sockets 51. As in the case of the arm members this means may comprise elastic bands 71 extending through the axial bores 61 of the plugs

57 and extensions 58 and into the axial bores 69 of the sleeve 68. The bands 71 may have their one end connected with pins 72 lying in engagement with the end faces of the extensions 58 and may have their other ends connected with the hooked ends of fastening pins 73 extending through the axial openings 70 of the reinforcing members 65, said pins 73 preferably having heads 74 located in recesses 75 with which said reinforcing members 65 are provided.

The sockets for the arm and leg members may be provided in the body 10 in any convenient manner; for instance, the body material may be molded to form the sockets 26—51, the sleeve sections 27—52, and the flanges 28—53 as indicated by solid lines in Fig. 4, or the body material may be molded in the manner indicated by dotted lines in Fig. 4 and then inverted into the body 10 to properly provide the limb sockets and their associated elements; as shown in Fig. 3 the limb sockets may be produced by molding and in their initial condition may include outwardly projecting tubular sections *a* which subsequently may be cut to proper length to provide the sleeve sections and the flanges forming part of the respective sockets.

In Fig. 5, I have illustrated another arrangement of limb construction which may be substituted for those previously described or used in combination therewith. For purposes of simplicity, I will describe this additional arrangement in connection with the arm members, it being understood that the arrangement is applicable with equal efficiency to the leg members; the description accordingly is to be construed as covering both the arm members and the leg members. The arm members 37^a in the form under discussion are made of soft sheet rubber or other equivalent highly flexible material, such as a suitable fabric or the like, and are hollow and filled in the conventional manner with any suitable filling material 38^a. At their upper ends the arm members 37^a are formed with curved sections 39^a and continuing tubular or sleeve sections 42^a. Means whereby the necessary rigidity is given to the sections 39^a comprises approximately hemispherical supporting devices 40^a made of wood or other suitable rigid material. The members 40^a are provided with inwardly directed recesses 41^a into which the sections 42^a extend so as to lie in surface engagement with the walls of said recesses as shown in Fig. 5. The sections 42^a are clamped in place in the recesses 41^a by means of plugs or bearing member 76 provided with cylindrical extensions 77 dimensioned to fit into the recesses 41^a in a manner to securely clamp the sleeve sections 42^a in place therein. The plugs or bearing members 76 include axial bores 78 and are provided exteriorly with bearing surfaces 79 curved in a manner to properly fit the limb sockets previously described herein.

When combined with the bodies of the toy figures, the bearing members 76 are seated in the co-operating sockets with the surfaces 79 in engagement with the surfaces of said sockets. Any suitable means may be provided for maintaining the limb members in place in said sockets. For instance, as shown in Fig. 5, the members 40^a may be provided with openings 80 and connecting surface recesses 81 for the accommodation of metallic or other loops 82, as shown in Fig. 5. The aforesaid means as illustrated further includes S-hooks 83 connected with the loops 82 and in turn connected with the opposite

ends of elastic bands 34 respectively. That is to say, one end of a given elastic band 34 may be connected with the hook 83 of one limb and its other end may be connected with the hook 83 of the opposite corresponding limb member. Obviously this is only an example of the means for maintaining the parts in an assembled condition and is not in any sense intended to define the only way in which this may be done.

In Fig. 6 I have shown another form of novel neck construction which may be substituted for the arrangement illustrated in Figs. 1 and 2, and which comprises a neck member or sleeve 14^a of wood or other suitable material provided at one end with a sloping annular flange 15^a; at its other end the member or sleeve 14^a is formed with a preferably flat end face 16^a. An axial bore or recess 17^a extends through the member or sleeve 14^a from the end face 16^a thereof to a recess 19^a formed in the bottom or inner end face of the neck member or sleeve 14^a as illustrated in Fig. 6.

The neck member or sleeve 14^a, in the assembled condition of the parts, is located within the neck section 12^a of the body in interior surface engagement with said neck section 12^a as shown. The latter, in other words, extends over said neck sleeve 14^a and is turned inwardly to form an inwardly directed annular flange 13^a which extends over the end face 16^a of said neck sleeve 14^a in surface contact therewith.

The material of the neck section 12^a is clamped on the sleeve or member 14^a by means of a bearing member 20^a which projects over the end face 16^a and includes a tubular extension 20^b dimensioned to snugly fit into the bore or recess 17^a of the sleeve or member 14^a. In its operative position the bearing member 20^a engages the flange 13^a of the neck section 12^a and clamps it in place against the end face 16^a of the sleeve or member 14^a and is fixed in clamping position by the extension 20^b in the bore 17^a. In some instances the flange 13^a of the neck section 12^a may be continued into the bore 17^a in surface engagement with the wall thereof so as to be engaged and clamped in said bore 17^a by the tubular extension 20^b as will be obvious.

In any case the bearing member 20^a is provided with a preferably curved bearing surface 20^b on which the head 22^a is movably mounted. Any suitable means, for instance as shown in

Fig. 1 and described hereinbefore, may be provided for movably maintaining the head 22^a in place on said bearing member 20^a.

While I have described the various novel features specifically in connection with a toy doll, it will be obvious that they may be incorporated with equal efficiency in other toy figures such as toy animals in such manner that said toy figures will very closely approximate the originals of which said figures are copies. In all forms the toy figures accordingly present not only a most natural appearance, but embody characteristics closely simulating those of the human or animal bodies constituting the originals of the toy bodies in question.

Although the present invention has been described in conjunction with preferred embodiments, it is to be understood that modifications and variations may be resorted to without departing from the spirit and scope of the invention, as those skilled in the art will readily understand. Such variations and modifications are considered to be within the purview and scope of the claim.

25 I claim:

In a toy figure, a rigid reinforcing member provided with an end surface of circular concave form and having an annular recess open at said end surface, and an axial opening extending from said annular recess, a body of highly flexible material having an integral circular concave portion lying in surface engagement with the concave end surface of said reinforcing member to constitute a limb socket on said body, a sleeve section forming an integral extension of said concave portion of said body material projecting into said annular recess in surface contact with the wall thereof, an annular inwardly directed flange forming an integral part of said sleeve section and resting in engagement with the bottom of said recess, a plug fitted into said recess for clamping said sleeve section and annular flange therein and provided with a circular concave face forming together with the circular concave portion of said body material said limb socket, and an extension projecting from said plug into said axial opening in frictional engagement with the wall thereof to fix said plug in its operative position.

JOSEPH L. KALLUS.
